(57) **CLAIM**

The ornamental design for a shopping cart infant seat, as shown and described.

DESCRIPTION

FIG. 1 is a top-front perspective view of a shopping cart infant seat according to my new design;

FIG. 2 is a side elevation view thereof, the opposite side elevation view being a mirror image;

FIG. 3 is a top plan view thereof;

FIG. 4 is a bottom plan view thereof;

FIG. 5 is a front elevation view thereof;

FIG. 6 is a rear elevation view thereof;

FIG. 7 is a top-rear perspective view thereof;

FIG. 8 is a bottom-rear perspective view thereof; and,

FIG. 9 is a bottom-front perspective view thereof.
